UNITED STATES PATENT OFFICE.

WILLIAM P. BARTEL, OF WALTHAM, MASSACHUSETTS.

DESIGN FOR A LACING-HOOK.

41,123.

Specification for Design.

Patented Jan. 24, 1911.

Application filed October 14, 1909. Serial No. 522,685. Term of patent 14 years.

To all whom it may concern:

Be it known that I, WILLIAM P. BARTEL, a citizen of the United States, residing at Waltham, in the county of Middlesex and State of Massachusetts, have invented a new, original, and ornamental Design for Lacing-Hooks, of which the following is a specification, reference being had to the accompanying drawings, forming part thereof.

Figure 1 is a plan view of a lacing hook,

showing my new design. Fig. 2 is a perspective view of the lacing hook.

I claim—

The ornamental design for a lacing hook, as shown.

WILLIAM P. BARTEL.
